US0D1068813S

(12) **United States Design Patent** (10) **Patent No.:** **US D1,068,813 S**
(45) **Date of Patent:** **** Apr. 1, 2025**

(54) **DISPLAY PANEL WITH GRAPHICAL USER INTERFACE**

(71) Applicant: **ART SHALOM INC.**, Seoul (KR)

(72) Inventor: **Zi-Hye Shin**, Seoul (KR)

(73) Assignee: **ART SHALOM INC.**, Seoul (KR)

(**) Term: **15 Years**

(21) Appl. No.: **29/901,814**

(22) Filed: **Sep. 6, 2023**

(30) **Foreign Application Priority Data**

Aug. 17, 2023 (KR) 30-2023-0032035

(51) **LOC (15) Cl.** **14-04**

(52) **U.S. Cl.**

USPC **D14/494**

(58) **Field of Classification Search**

USPC D14/485-495; D20/23, 24, 30

(57) **CLAIM**

The ornamental design for a display panel with graphical user interface as shown and described.

DESCRIPTION

The patent or application file contains at least one drawing executed in color. Copies of this patent or patent application publication with color drawing(s) will be provided by the Office upon request and payment of the necessary fee.

The sole FIGURE is a front view of a display panel with graphical user interface showing my new design.

The broken lines in the drawing show a display panel, and form no part of the claimed design.

1 Claim, 1 Drawing Sheet
(1 of 1 Drawing Sheet(s) Filed in Color)
